UNITED STATES PATENT OFFICE.

IRV J. KUERT, OF LOS ANGELES, CALIFORNIA.

ADJUSTABLE AND INTERCHANGEABLE FORM FOR HOLLOW WALL CONSTRUCTION.

Application filed February 9, 1925. Serial No. 7,855.

This invention relates to adjustment and interchangeable forms for hollow wall construction.

The general object of the invention is to provide an improved form which may be used for the purpose of constructing building structures with hollow portions.

One of the specific objects of the invention is to provide an improved form member wherein a plurality of members are arranged to provide a closed form and wherein a novel means is provided for causing contraction of the form.

A further object of the invention is to provide a form wherein novel spacing members are provided for holding the form in expanded and collapsed position.

A further object of the invention is to provide a multiple unit hollow form whereby the long forms may be readily removed from a structure.

Other objects of the invention will be apparent from the following description taken in connection with the accompanying drawings wherein Fig. 1 is a section of a portion of a building structure showing the use of my invention; Fig. 2 is a fragmentary elevation of a portion of one of my interchangeable forms; Fig. 3 is a top plan view of one of the forms; Fig. 4 is a view similar to Fig. 2 showing the parts in another position; Fig. 5 is a fragmentary elevation of a unit composed of two members showing the members in operative position; Fig. 6 is a view similar to Fig. 5 showing the members in the act of being removed; Fig. 7 is an enlarged detail showing the manner in which the two portions of the unit are superimposed; Fig. 8 is a section on line 8-8, Fig. 4; Fig. 9 is a plan view of a wrench; Figs. 10 and 11 are fragmentary elevations showing a modified form of operating bar; Fig. 12 is a top plan view showing a further use of my invention; Fig. 13 is a sectional detail of a modified form and Fig. 14 is a section on line 14-14, Fig. 2.

Referring to the drawing by reference characters, I have shown a form embodying the features of my invention at 10. This form comprises as shown in the preferred form, four wall members 11, 12, 14 and 15. Each of these wall members as will be seen by referring to Fig. 3 comprises a side portion and an end portion.

The wall members overlap at the sides and

at the ends to form a body which is closed except at its ends. The form held in the position shown in Fig. 3 by a mechanism to be presently described, is used in building construction and after the material, which may be concrete, has been placed around it, and has cured, the form is removed by first contracting it so that it is reduced in cross sectional area after which the form may be removed.

Before my invention forms for making hollow walls have been used but my improved form, in addition to its use single also enables me to build up a unitary form comprising several connected forms which are so related that by continuous operation the members may be successively reduced in diameter and removed by a single operation. This is an important feature, as it allows structures to be made wherein very long openings or cells are provided. The unit feature also allows one to make drains and sewers by pouring them in their complete state.

Referring again to the drawing and particularly to Figs. 2 and 4, it will be seen that upon the wall members 12, 13, 14, and 15, I provide supporting members 20. These supporting members, as shown, are small angle irons which have one web secured to the wall members while the other web projects up from these members. These supporting members are apertured to receive operating rods 21. These operating rods are spaced apart and are freely mounted in the apertures and may turn and also may have longitudinal movement in these apertures. In order to hold the rods in the position indicated. I provide springs 22 shown as flat springs which are fitted over the rods and held by fastening members 23. These fastening members 23 as shown in Fig. 8 comprises washer-like discs which are fitted in slots on the rods 21. The ends of the springs may be secured to the supporting members 20 by fastening members 24, or they may be loose at the outer ends if desired.

Adjacent the inner edge of the members 12, 13, 14 and 15 I arrange longitudinally extending actuating members 30. These members like the members 20 are preferably in the form of angle irons and each has one web secured to inner walls of the wall members 12, 13, 14, and 15. The actuating members 30 like the supporting members 20, are

apertured to receive the operating rods 21.

From the foregoing description and from an examination of Fig. 2 it will be apparent that each half of the form is supported in assembled position by means of the supporting members 20 and the actuating members 30, united through the operating rods 21.

The actuating members 30 are provided at spaced intervals along their opposed faces 10 with cams 32. In order to provide means for engaging the cams 32, I provide an operating bar 35. This operating bar is provided with cam surfaces on both faces thereof as shown at 36. These cam surfaces 15 engage the cams 32 when the operating bar 35 is moved longitudinally and hold the wall members in extended relation against the tension of the springs 22. When the operating bar is moved vertically the springs 22 force 20 the supporting members 20 toward each other thus moving the wall members 12, 13, 14 and 15 toward each other.

Although in Fig. 2 I have shown but wall members 12 and 13, it will be understood 25 that these wall members are arranged opposite the wall members 14 and 15 which are of similar construction.

The operating bar 35 is of considerable width and is provided with the cam surfaces 30 adjacent each edge thereof so one bar operates the cam 32 on all the four wall members 12, 13, 14, and 15 to increase and decrease the width of the form.

In order to move the wall member 12 toward the wall member 15 and to move the wall member 13 toward the wall member 14 to increase and decrease the thickness of the form, I provide slots 40 in the actuating bar 35. These slots have cam surfaces 41 therein and the slots are formed to receive the operating rods 21. By referring to Figs. 5 and 6 it will be seen that in the former figure the operating rods 21 are shown adjacent the top of the slots 40. This causes the wall members 12 and 15 and 13 and 14 to be spaced in their extreme position. When the operating bar 35 is raised to the position shown in Fig. 6, the operating rods 21 move along the slot 40 to the position shown 45 in this figure and the cam surface 41 of the slot 40 brings the operating rods 21 toward each other thus bringing the wall members 12 and 15 toward each other and also bringing the walls 13 and 14 simultaneously toward each other.

In order to assemble the device the slots 40 are shown as open ended. This enables the operating bars to be readily inserted in position. The position of the parts is such 60 that normally the operating rods 21 are spaced from the ends of the slots 40 so that the whole device will not readily collapse.

In order to lift the operating bar 35 I show a handle mechanism 45 which is pivoted as at 46 upon a bracket 47 supported

on the operating bar 35. A link 50 is eccentrically mounted upon the handle member 45 at one end and at the other end engages an actuating member 30 as shown in Fig. 4. When the operating handle 45 is rocked 70 it will be seen that the operating bar 35 will be raised or lowered relative to the wall members 12, 13, 14, and 15, depending on the direction of the movement of the handle.

Adjacent the top of the form, I show a 75 cross bar 55. The operating bar 35 extends through this cross bar. The cross bar has suspended thereon a pair of auxiliary operating bars 56. These auxiliary operating bars 56 like the primary operating bar 35 80 have slots 40 provided with cam surfaces. These slots engage over the operating rods 21 and assist in the operation thus supplementing the action of the operating bar 35.

I preferably provide a plurality of the 85 cross bars 55 which are arranged at spaced intervals along the form to provide rigidity and in order to maintain a correct alignment of the auxiliary operating bars 56 on the bars 55 to arrange angle members 57 which 90 are secured to the wall members 12, 13, 14, and 15.

In order that the device may be used as a unit for work where a long form is desired, I arrange upon the lowermost portions of 95 the operating bars 35 and 56 a plurality of rings 60. These rings are adapted to be connected through a snap member 61 with a chain 62 fastened to the top of the bars 35 and 56 on the underneath form. The middle chain it will be noted, is arranged when the form is in use, beneath the operating handle 45 and in fact fits within a groove within this operating handle as shown in Fig. 14.

105 From the foregoing description it will be apparent after the concrete has set, I may first actuate the uppermost handle 45 thus reducing the cross sectional area of the uppermost form. Continually pulling on this form will tighten the chains beneath this form thus raising the underneath handle and causing the underneath form to be substantially reduced in size. This operation will be repeated in continuous succession until 110 all of the forms have been removed.

115 Instead of a single wide operating bar, I may use a pair of narrow bars as shown in Fig. 10. Each of these bars shown at 70 is provided with slots 40 and in order to hold the bars spaced, I secure upon the opposed face thereof links 71 which may be fixed as at 72 to the bar and may be pivotally united by a pin 73. Apertures 74 arranged in series along the bar 70 are adapted 120 to receive pins 75 which secure the ends of the links 71 thus allowing the bar 70 to be held in spaced relation.

125 In Fig. 12 I show a slight modification of my invention wherein I provide interposed 130

plates 80 and 81 between the wall members 12 and 13. The plates 80 and 81 are provided with longitudinally extending supporting members 82 in the form of angle bars. These members 82 are substantially the same as the members 20 and function in the same manner. In this way, I may provide for cores of varying size. It will also be apparent that by using a plurality of my devices side by side that I can provide for cores of any desired size.

In order to provide proper alignment of the cores when used as a unit, I provide guides 88 on the bottom of the wall members. The guides fit in the upper part of each superimposed form.

Referring to Fig. 13 it will be seen that instead of the springs 22 I may use a coil spring 84 which may be secured upon the operating loads 21.

Having thus described my invention, I claim:

1. In a building form, a plurality of rigid wall members, each consisting of a strip of metal, each of said strips being bent to form two portions arranged at right angles to each other, means disposed within said wall members to hold said members in position, means to alter the cross sectional area of the form in two dimensions, means to lock said form in one position and resilient means to urge certain of said walls in one direction.

2. In a building form, a plurality of wall members, each of said members comprising four angularly shaped members, each having both ends thereof overlapping intermediate the sides of the form to form a hollow rectangular box-like form, means within said form to cause said overlapping portions to move to contract said form, said means comprising longitudinally extending actuating members, and transversely extending operating rods, and means to move said actuating members and said operating rods.

3. In a collapsible form, oppositely disposed rigid wall members, each comprising a side portion and an end portion, arranged at right angles to each other, supporting members extending longitudinally of said wall members, operating rods passing through said supporting members, an actuating member on each of said wall members, an operating bar, means on said operating bar for moving the actuating members to alter the size of the form.

4. In a building form, a plurality of wall members, each of said members comprising portions arranged at right angles to each

other and having their ends overlapping to form a hollow rectangular box-like form, means within said form to cause said overlapping portions to move to contract said form, said means comprising longitudinally extending actuating members and transversely extending operating rods, an operating bar and means on said operating bar coacting with said actuating members and said operating rods to cause said wall members to slide along their overlapping faces.

5. In a collapsible form, four wall members disposed opposite each other in pairs, each member comprising a side portion and an end portion, supporting members extending longitudinally of said wall members, operating rods passing through said supporting members, an actuating member on each of said wall members, an operating bar, coacting devices on said operating bar and said actuating members and other coacting devices on said operating bar and said operating rods.

6. A unitary form comprising a plurality of collapsible forms, each having four oppositely disposed wall members, each wall member comprising a side portion and an end portion, supporting members extending longitudinally of said wall members, operating rods passing through said supporting members, an actuating member on each of said wall members, an operating bar, means on said operating bar for moving the actuating members to alter the size of the form, means to operate the operating bar, and means to connect the last mentioned means in adjacent forms.

7. In a collapsible form, four oppositely disposed wall members, each comprising a side portion and an end portion, supporting members extending longitudinally of said wall members, operating rods passing through said supporting members, an actuating member on each of said wall members, an operating bar, said operating bar having cams thereon, cams on said actuating members coacting with the cams on the operating bar, said operating bar having cam grooves therein, said cam grooves being associated with said operating rods, auxiliary operating bars adjacent said first mentioned bar, said auxiliary bars having cam slots therein, similar to the cam slots in the first mentioned operating bar, and means to move said operating bar.

In testimony whereof, I hereunto affix my signature.

IRA J. KUERT.
